UNITED STATES PATENT OFFICE

WILLIAM H. SHERMAN, OF METHUEN, MASSACHUSETTS, ASSIGNOR TO U. S. BOBBIN & SHUTTLE COMPANY 1929, OF PROVIDENCE, RHODE ISLAND, A CORPORATION OF RHODE ISLAND

SHUTTLE-EYE GUARD

Application filed March 13, 1930. Serial No. 435,598.

This invention relates to shuttles. It is particularly applicable to shuttles of the self threading or automatic type in which there is a diagonal threading slot leading out to an eye in the wood, associated with a metal threading block which forms part of the top of one side of the threading slot.

My purposes are to provide a lining for the outlet of the threading slot, or what we call the eye in the wood, of a character which will not be cut nor worn by the thread, but will allow the thread to run freely and will protect the wood; and also to provide a locking device or tooth which will allow the shuttle to thread without difficulty but will lock the thread in place after the first or second pick.

In the drawings, Fig. 1 is a plan view of the front end of a shuttle with my device in position.

Fig. 2 is a side elevation of a shuttle such as shown in Fig. 1 as viewed from the bottom of Fig. 1.

Fig. 3 is an elevation from the back of my device removed from the shuttle.

Fig. 4 is a sectional elevation as viewed from the right of line 4—4 of Fig. 3.

Fig. 5 is a front elevation of my device removed from the shuttle.

Fig. 6 is an elevation as from the right of Fig. 5.

Fig. 7 is a view from the bottom of a shuttle block such as I prefer to use with my device.

Fig. 8 is a perspective of a modified form of shuttle guard.

Fig. 9 is a side elevation similar to Fig. 2 of a shuttle with the type of shuttle guard shown in Fig. 8 in place.

In the drawings, A represents the wooden part of a shuttle which has the usual metal tip 10, bobbin recess 11, threading block recess 12 for the threading block B, threading recess 13 and threading slot F which extends diagonally backward from recess 13 and terminates at the side of the shuttle in an eye in the wood indicated by 15.

16 indicates the front wall of this threading slot F and near the rounded end 17 of front wall 16 is a vertical recess 18 part of

which extends down at 19 as a point to receive the front bend 38 and point 39 of my eye lining C to be described.

Preferably the top surface adjoining the bend 38 and wall 16 are smooth and rounded and merge one with the other.

The back wall is rounded and indicated by 14.

B represents a shuttle block of a well known type having a sloping top guide wall 21, nose 20 from which extends backward the front wall 24 which forms part of the back wall of the threading slot F and preferably without any break or opening merges with the rest of the back wall 14 of slot F.

27 represents what I will call a wing formed by wall 24 and the back wall 26, as shown in Fig. 7, which come together at 25.

Adjoining and underneath this wing tip 25 is a recess 29 to receive the upper end 34 of the back arm 30 of my metal eye lining C.

This eye lining is made of relatively flat sheet metal and includes the front arm 32 and back arm 30 united at the bottom 35 thus forming a U shaped member.

Back arm 30 terminates at the top 34 in a straight end which may be slightly beveled off either to fit into a recess 29 in the under part of block B or merely to rest against such under part in back of wing tip 25.

The front arm 32 is cut away at a slant at 33 and is bent over and forward at 38 and thence down at 39 to form a tooth. Bend 38 enters the recess 18 and tooth 39 enters tooth hole 19 as described.

I prefer to use a holding tooth 36 which as shown is forced out, back and down from front arm 32 leaving a passage 37.

The tip 136 of this tooth enters a suitable hole or recess 31 in back arm 30 which is of such size that the thread can pass around the tip 136 as it slides down the top of tooth 36 and around so as to get below tooth 36 for the normal operation of the shuttle.

With the construction shown in Figs. 1 to 7, the recess L in the wood A of the shuttle is so cut that lining C can be forced down from the top before the block B is put in position and held in place by the usual screw H.

Lining C cannot escape unless block B is removed.

However, as shown in Fig. 8, I can use a modified construction in which the front arm 42 and back arm 40 are curved around somewhat in S shape and terminate at 48 and 44 the arms being connected at 45 and the holding tooth 46 being bent out leaving hole 47 and extending back into the recess or hole 41 in back arm 40.

10 This type of lining is pushed in from the side instead of down from the top and has no holding tooth corresponding with 39 and no front arm bend corresponding with 38.

15 Fig. 9 shows this lining in place in a shuttle.

I claim:

1. The combination in a self threading shuttle having a wooden body with a threading slot which terminates as an eye in the wood; of a threading block which forms part of the top of one side of said threading slot; with a metal eye lining which fits the eye in the wood and is of substantially U shape 20 having a back arm which extends up into a recess in the under side of said threading block and also has a tooth recess, said lining also having a front arm which extends up and is bent forward and down into the wood, said 25 front arm also having a holding tooth extending from the front arm down and back into the tooth recess in the back arm.

2. The combination in a self threading shuttle having a wooden body with a threading slot which terminates as an eye in the wood; of a threading block which forms part 30 of the top of one side of said threading slot; with a metal eye lining which fits the eye in the wood and is of substantially U shape having a back arm which extends up under said 35 threading block and also has a tooth recess, said lining also having a front arm which has a holding tooth extending from the front arm down and back into the tooth recess in the back arm.

40 In testimony whereof I have affixed my signature.

WILLIAM H. SHERMAN.
